UNITED STATES PATENT OFFICE.

GEORGE W. BEATTY, OF DECATUR, ILLINOIS.

FUSE-SETTING MACHINE.

Application filed March 29, 1926. Serial No. 98,286.

(GRANTED UNDER THE ACT OF MARCH 3, 1883; 22 STAT. L. 625.)

This invention relates to a fuse setting machine of the type which is provided with two relatively rotatable adjusting members, a crank for independently rotating the member which is coupled to the time ring of the fuse and a worm gear for rotating the other member which is coupled to a fixed part of the fuse. The adjustment of the fuse is effected by causing the time ring 5 adjusting member to carry out two complete revolutions while the other member is either stationary or may be under continuous operation.

In the known devices of this character 15 the crank is accustomed to be manually released while no positive means are provided for preventing more than two revolutions. These defects make it possible to secure inaccurate fuse settings which condition is a 20 matter of serious moment in anti-aircraft gunnery because of the very short period during which targets of this character remain in range.

With a view to correcting these defects, 25 the fuse setting machine of the present invention is arranged to be normally locked against operation until the insertion of a round automatically unlocks the crank which is then positively restricted to its setting 30 movement as long as the round remains in the machine. Correspondingly the removal of the round permits the unlocking mechanism to be restored to normal position. Such an arrangement also enables the continuous adjustment of the member connected 35 to the fixed part of the fuse irrespective of the movement of the crank and provision is made whereby the adjustment may take place in either direction to increase or 40 decrease the fuse setting.

With the foregoing and other objects in view, my invention resides in the novel arrangement and combination of parts and in the details of construction hereinafter described and claimed, it being understood 45 that changes in the precise embodiment of the invention herein disclosed may be made within the scope of what is claimed without departing from the spirit of the invention.

50 A practical embodiment of my invention is illustrated in the accompanying drawings, wherein:

Fig. 1 is a longitudinal sectional view of my improved fuse setter with a round inserted therein and the crank unlocked; 55

Fig. 2 is a similar view showing the normal disposition of the parts when the round is removed and the crank is in position of rest;

Fig. 3 is a plan view; 60

Fig. 4 is a sectional view on the line 4—4 of Fig. 1;

Fig. 5 is an end view;

Figs. 6 and 7 are sectional views respectively on the lines 6—6 and 7—7 of Fig. 1; 65 and

Fig. 8 is a side view of the time fuse for which the machine is designed.

Referring to the drawings by numerals of reference:

The fuse setter consists essentially of a housing 4 in which two adjusting members 5 and 6 are independently rotatable about the axis of the machine. The member 5 is adapted to be coupled to the adjustable part 75 of the fuse, namely, the rotatable ring 7, while the member 6 is adapted to be coupled to a fixed part of the fuse, for example, the base 8. For the purpose of coupling the adjusting members to the corresponding 80 parts of the fuse, the members 5 and 6 are each provided with a pair of spaced oppositely disposed bell crank levers, respectively 5^a and 6^a for engaging corresponding lugs 7^a and 8^a on the respective parts 85 of the fuse. The levers of each set are so formed with relation to the adjusting members that a single spring 5^b or 6^b, whose ends are engaged in arms of the levers, 90 serves to yieldingly hold the levers in lug engaging position. If when the fuse is introduced into the machine the lugs are located in proximity to the lug engaging ends of the levers they will strike the beveled surfaces 5^c or 6^c of one of the levers and 95 thus effect their entry or prepare themselves for entry between the spaced ends of the levers.

In order that the fuse setter may be capable of engaging and setting the fuse irrespective of the position of the lugs with respect to each other, or to the machine, the adjusting member 5 is directly connected to a crank 9 for rotating the member whose

levers 5^a are thus caused to pick up the lug 7^a on the time ring and place it in a predetermined position while at the same time a rotational movement will be imparted to the round until the fixed lug on the base of the fuse snaps into engagement with the levers of the adjusting member 6. In order to insure that the round will be rotated sufficiently for the fixed lug to pick up the 10 levers on the member 6, it is necessary to move the crank through two complete revolutions, and it is this circumstance that gives rise to certain of the improvements of the present machine.

15. However, before taking up such features it should be first stated that a worm 10 serves for imparting to the member 6 an angular position relative to the predetermined position of the member 5 which corresponds to 20 the desired location of the bursting point. And by reason of the fact that the member 6 can be moved to increase or decrease such relative position, it is possible to continuously manipulate the worm to change the fuse 25 setting so that any change in fuse range which may be announced to the fuse range operator may be imparted to the fuse as long as the round remains in the machine.

Disposed axially within the adjusting 30 member 5 is a spring pressed plunger 11 constrained to be rotated with said member by means of a pin 12 disposed in a slot 13 in the member and normally held in the position shown in Fig. 2. The plunger is formed with a concave face 14 for receiving the nose of the fuse and when the round is fully inserted it forces the plunger to the position shown in Fig. 1. Mounted loosely on the shank of the plunger, but held against longitudinal movement by a combined guide and 35 stop member 15 for the plunger is a ring 16 provided with an arm 16^a disposed in a slot 17 in the member 5. The arm is formed with a cam face 16^b so that when the plunger 40 is retracted on being struck by a round, the arm will actuate a cam follower or bolt 18 mounted in the housing 4 perpendicular to the axis of the adjusting member 5 and normally held depressed by a spring 19 into the 45 slot 17 of the member.

50. Associated with the bolt is a spring pressed latch 20 engageable in a recess 21 formed in a plate 22 on the crank for the purpose of holding the crank in position of rest. When the cam arm 16^a raises the bolt, the latch mounted therein will accordingly be moved from its recess in the crank which is then free to be turned. Inasmuch as the 55 crank is to be uninterruptedly operated through two revolutions, some means must be provided to hold the latch and bolt in the elevated position clear of the plate 22 on the crank and the cam arm 16^a of the adjusting member 5 (see Fig. 4) at the commencement 60 of the second turn of the crank. This may

be accomplished by means of a Geneva wheel 23 pivotally secured to the housing and arranged to be given a quarter turn by means of a pin 24 on the crank where it is held against spinning by a plunger 25 engageable in correspondingly spaced recesses in the wheel. This arrangement causes the large tooth on the Geneva wheel to be moved into position to engage and hold the bolt and latch in the elevated position during the 70 first revolution of the crank and by the same mechanism, that is, by the pin 24 the wheel will be tripped at the commencement of the second revolution to present the short tooth of the Geneva wheel under the bolt, so that the latch 20 will be free to drop into the path of the plate 22. Consequently as the crank is terminating its second revolution, the bevel face 22^a on the plate 22 strikes the latch which is retracted and brought up 80 against the stop shoulder 22^b on the plate in a position where it immediately snaps into the recess 21 to positively limit the movement of the crank. The bolt 18 and adjusting member 5 are also organized so as to insure the arresting of the crank at the proper moment. As seen most clearly in 85 Fig. 4 the member 5 is formed with a groove 26 so that as the crank and member 5 are approaching the termination of their setting 90 movement, the Geneva wheel having been tripped to release the bolt, the bolt is free to follow this groove until the cam arm 16^a 95 rotating with the adjusting member 5 comes up against it as indicated in dotted lines in Fig. 4. This is the position of rest of the 100 crank and when thus brought up the member 5 has been rotated to position the lug on the rotatable time ring of the fuse at the predetermined point.

To fully restore the mechanism to initial 105 position the round is removed, whereupon the plunger is automatically restored to initial position (Fig. 2), and by the action of the torsion spring 27 the ring 16 is slightly 110 rotated until the arm 16^a is brought up against the edge of the slot 17 in the member 5 (Fig. 4) where it will be lined up with the bolt so that upon introduction of the succeeding round it will again raise the bolt in 115 repeating the cycle.

During the initial movement of the crank 120 the plunger 11 by reason of its connection with the member 5 through the pin 12 and its connection with the ring 16 through the torsion spring 27, will immediately be moved out from under the bolt and as the Geneva wheel has not yet been actuated to retain the bolt in the elevated position the bolt and with it the latch would instantly be lowered 125 by its spring 19 to engage in front of the face 28 defining the slot in member 5. To avoid this, the plate 22 on the crank is extended to support the latch until the member 5 is moved sufficiently to pass under the 130

bolt whence the bolt will be held elevated by riding on the periphery of the adjusting member until such time as the Geneva wheel is brought into operation.

- 5 In using the machine to set a fuse the operator of the crank maintains a pressure thereon so that as soon as a round is inserted he will immediately turn the crank through two revolutions after which it is positively arrested and can not again be actuated until the round is removed and a new round introduced. The fuse range operator in the meantime is engaged in continuously manipulating the adjusting member 6 according to 10 the announced range and consequently the fuse is in continuous adjustment until the round is removed from the machine preparatory to inserting it in the chamber of the gun.
- 15 The bolt 18 does not necessarily have to be associated with the adjusting member 5 in so far as its function of unlocking the latch is concerned. It could be independent of any coordinate action with this adjusting member and the cam 16^a could likewise be directly formed on the plunger.
- 20 I claim:

1. A fuse setting machine embodying an adjusting member formed with a slot and a groove, a crank for driving the same, a spring pressed bolt normally positioned in the slot of the adjusting member, a spring pressed latch in the bolt and normally engaging the crank, a plunger within the adjusting member adapted to be retracted when struck by a round introduced into the machine, a member mounted on the plunger and having a cam arm disposed in the slot of the adjusting member, said arm adapted 25 to disengage the bolt and latch when the plunger is retracted, means whereby the bolt is prevented from entering the slot on the first revolution of the crank and adjusting member, said means rendered inoperative as the crank commences its second revolution to permit the bolt and latch to function and means for restoring the cam arm to initial 30 position when the plunger is released by withdrawal of the round.

35 50 2. A fuse setting machine embodying a rotatable adjusting member, a bolt normally engaged with the adjusting member to prevent movement thereof, a plunger within the adjusting member adapted to be retracted when struck by a round introduced into the machine, a cam member mounted 40 on the plunger for movement with the adjusting member, said cam member adapted to disengage the bolt when the plunger is 45 retracted, means whereby the bolt is held disengaged during the first revolution of the adjusting member, said means rendered inoperative during the second revolution of 55 said member to permit re-engagement of the bolt and means for restoring the cam mem-

ber to initial position when the plunger is released by withdrawal of the round.

3. A fuse setting machine embodying a rotatable adjusting member, a bolt normally engaged with the adjusting member to prevent movement thereof, a plunger rotatable with the adjusting member and adapted to be retracted when struck by a round introduced into the machine, means carried by the plunger for disengaging the bolt when the plunger is retracted and means whereby the bolt may arrest the adjusting member on termination of the setting movement.

4. A fuse setting machine embodying a rotatable adjusting member, a bolt normally engaged with the adjusting member to prevent movement thereof, a plunger adapted to be retracted when struck by a round introduced into the machine, means carried by the plunger for disengaging the bolt when the plunger is retracted and means whereby the bolt is subsequently released into the path of the adjusting member while the plunger is retracted.

5. A fuse setting machine embodying a rotatable adjusting member, a bolt normally engaged with the adjusting member to prevent movement thereof, a plunger adapted to be retracted when struck by a round introduced into the machine, and means carried by the plunger for disengaging the bolt when the plunger is retracted.

6. A fuse setting machine embodying a rotatable adjusting member, a bolt for normally holding said member against movement, means for holding the bolt in disengaged position during the first revolution of the adjusting member and means whereby said bolt is released to limit said member to two revolutions.

7. A fuse setting machine embodying a rotatable adjusting member, a bolt for normally holding said member against movement, means actuated by a round for disengaging the bolt, and means for holding it disengaged, said means rendered inoperative after a predetermined angular movement is imparted to the adjusting member.

8. A fuse setting machine embodying a rotatable adjusting member, a bolt for normally holding said member against movement, means actuated by a round for disengaging the bolt and means for holding it disengaged, said means rendered inoperative through movement of the adjusting member to permit reengagement of the bolt.

9. A fuse setting machine embodying a rotatable adjusting member, locking means for normally holding said member against movement and round actuated means within the adjusting member for disengaging the locking means.

10. A fuse setting machine embodying a rotatable adjusting member, locking means for normally holding said member against

movement and round actuated means rotatable with the adjusting member for disengaging the locking means.

11. A fuse setting machine embodying a rotatable adjusting member, locking means for normally holding said member against movement and round actuated means for disengaging the locking means.

12. A fuse setting machine embodying a rotatable adjusting member, a pair of spaced fuse engaging members mounted in said adjusting member and a single spring for holding both of said engaging members in driving position.

GEORGE W. BEATTY
